UNITED STATES PATENT OFFICE.

LAWSON M. FULLER, OF NEW YORK, N. Y.

BLANK CARTRIDGE.

SPECIFICATION forming part of Letters Patent No. 604,824, dated May 31, 1898.

Application filed February 24, 1897. Serial No. 624,889. (No model.)

To all whom it may concern:

Be it known that I, LAWSON M. FULLER, a citizen of the United States, residing at New York, in the county of New York and State of New York, have invented a certain new and useful Improvement in Blank Cartridges, of which the following is a specification.

My invention relates to a new and useful improvement in blank cartridges, and has for its object to make a cartridge of this description which may be used in a magazine or repeating rifle and which shall at the same time be cheaper and safer than cartridges heretofore used for this purpose.

15 In the single-loading rifle the blank cartridge is usually inserted in the bore by hand, and the form of its point does not necessarily differ greatly from that of an empty shell. In a magazine or repeating rifle, however, the 20 cartridge is loaded by mechanical means, and the form and length of the blank must closely approximate that of the ball-cartridge.

I successfully attain the object of my invention by the details of construction and 25 combination of elements hereinafter set forth, and then specifically designated by the claim.

In order that those skilled in the art to which this invention appertains may understand how to make and use the same, its 30 construction and operation will now be described in detail, referring to the accompanying drawing, forming a part of this specification, in which—

Figure 1 shows a view in side elevation of 35 a cartridge made in accordance with my improvements. Fig. 2 is a longitudinal sectional view.

In manufacturing the projectile-shaped part of the cartridge I roll paper around a 40 mandrel until severallayers have been tightly wound. I then paste or glue the outer edge of the paper and slip the completed form from the mandrel. This form is preferably that of a hollow frustum of a cone. The paper so formed is then subjected to the action of a 45 punch and die, when it is pressed to produce a casing A, slightly reduced at its inner end, the body portion tapering gradually toward the outer end, the forward portion being

formed in sections, each of said sections being 50 of less diameter than the portion immediately preceding, the foremost of said sections having its walls reduced in thickness, and said casing as a whole having its inner configuration conforming to the outer configuration. 55 Powder B is then placed within the casing and compressed to give stiffness thereto. The casing then has its reduced rear end fitted in the shell S, which is provided with the primer V. When placed in the gun, the shoulders 60 X, formed by the reduced sections, fit against corresponding shoulders or projections in the bore of the gun, and in action the firing-pin strikes against the primer V, exploding the same, which in turn ignites the powder within 65 the casing. The gas generated tears off the foremost section and forces it from the bore of the gun, said result being due to the reduction of the thickness of the walls of the foremost section and the support afforded by the 70 shoulders.

Now in my form of cartridge I obtain, first, a cartridge which may be made from fired cases or seconds of new manufacture and one which still has the form of the ball-cartridge, 75 and, second, by the compression of the powder the projectile portion is made sufficiently stiff to function properly in the gun and permit of rough usage, and at the same time the paper torn from the portion is completely expelled from the bore of the gun, so that no dangerous wad is left therein to form a projectile to be discharged by the next cartridge exploded.

Having thus fully described my invention, 85 what I claim as new and useful is—

In combination with a shell of shortened length, a casing having its rear end reduced and fitted in said shell, the body portion of the casing forming a continuation with the 90 shell and tapering gradually toward its outer end, the forward portion of said casing being formed in sections, each being less in diameter than that portion immediately preceding producing shoulders which fit against corresponding shoulders or projections in the bore 95 of the gun to prevent the outward passage of the rear portion of said casing, the foremost

section having its walls reduced in thickness, the inner configuration of the casing conforming to the outer configuration, a charge of compressed powder conforming to the inner configuration and lending strength to said casing, and a primer fixed in said shell, substantially as described.

In testimony whereof I have hereunto affixed my signature in the presence of two subscribing witnesses.

LAWSON M. FULLER.
